UNITED STATES PATENT OFFICE.

GRANT C. BLASDELL, OF TOWANDA, PENNSYLVANIA.

ROTARY EXPLOSIVE-ENGINE.

SPECIFICATION forming part of Letters Patent No. 743,230, dated November 3, 1903.

Application filed April 6, 1903. Serial No. 161,380. (No model.)

To all whom it may concern:

Be it known that I, GRANT C. BLASDELL, residing at Towanda, in the county of Bradford and State of Pennsylvania, have invented a new and Improved Rotary Explosive-Engine, of which the following is a specification.

My invention is in the nature of an improved engine operating under a power produced by the explosion of a suitable working agent (a mixture of gas or gasoline and air) of that type in which cooling liquids and fly-wheels are dispensed with and the motor so arranged that the cylinders, together with the actuating pistons or plungers, are rotated around a stationary shaft and adapted to replace the weight of the usual fly-wheels. Heretofore in engines of this type great difficulty has been experienced in introducing the working agent into the cylinders uniformly and under a proper admixture of the explosive gas and air.

My invention seeks to provide an improved construction of parts constituting an engine of the character stated which overcomes the difficulties heretofore mentioned and which possesses additional advantages in providing for a quick and effective cooling of the cylinders and the exhausts; and to these ends my invention in its generic nature comprehends an explosive-engine having the cylinders fixedly connected with a hollow casing and rotating with the casing and the plunger-pistons around a stationary hollow shaft and in which the pistons or plungers and the working-agent inlets and exhausts are correlative arranged to effect a regular and uniform preliminary compression of the working agent within the hollow casing under the back stroke of the plunger-pistons, and for utilizing the expansive force of the preliminary compressed charge to positively clear the explosion-chambers of the residuum or burned mixtures therein prior to a final compression of the working charge within the cylinders by the outward thrust of the plunger-pistons.

In its more complete nature my invention includes a peculiar co-operative arrangement of the cylinders, the crank-shaft, the plunger-pistons, and pitmen connections joined with a casing-contained crank-shaft, whereby the opposing pitmen connections or drive-

arms are always relatively the same distance from the wrist-pin or crank-centers and in which the several parts are so designed and to have such predetermined actuations where- 55 by the explosion of the working agent, as also the compression of the said agent prior to the explosion, acts against the centrifugal force of the drive-arms and plunger-pistons to materially relieve the strain upon the bearings 60 and in which the rotation of the casings or bed, the cylinders, &c., is acquired in a manner to save the energy usually lost in other engines of this type heretofore provided in throttling the high as well as the low speed of the 65 pistons and drive-arms.

Again, my invention seeks to provide a casing with the cylinders fixedly connected thereto and having a special internal construction for diffusing the exhaust, cooling the same 70 and the cylinders by the combined quick motion of the casing through the air, and a special means for circulating the air around the exhaust-discharge and for muffling the cylinders; and, finally, my invention embodies cer- 75 tain details of construction and peculiar combinations of parts, all of which will hereinafter be fully described, and specifically pointed out in the appended claims, reference being had to the accompanying drawings, in 80 which—

Figure 1 is an exterior perspective view of my improved explosive-engine. Fig. 2 is a vertical section of the same taken on the line 2 2 of Fig. 3. Fig. 3 is a transverse section 85 thereof on the line 3 3 of Fig. 2. Fig. 4 is a detail view of a portion of the casing of one of the cylinders and the plunger-piston operating therein, the latter being shown in the position to admit a working-agent charge 90 into the explosion end of the cylinder and for exhausting the prior burned residuum. Fig. 5 is a detail horizontal section taken on the line 5 5 of Fig. 4. Fig. 6 is a detail view 95 illustrating the igniting devices, and Fig. 7 is a detail view of a governor device operable by the change of speed of the rotary motor produced by the variation of the load on the engine.

In the practical construction my invention 100 embodies a cylindrical casing consisting of an annular portion A, in which are contained

the cylinders B B', the muffling-spaces C C', and the exhaust diffusing and cooling compartments, and the said annular portion A is firmly bolted to a central portion A', which 5 includes the piston-heads or hub-like extensions A², one (or both) of which is provided with a sprocket-wheel or drive-pulley a, and each of which has a long adjustable bearing a' a' for the diametrically oppositely disposed 10 hollow shaft-sections D D', the inner ends of which are fixedly connected with or integrally joined with the double crank members d d', as best shown in Fig. 1, by reference to which it will be seen that the cylinders B B' are disposed diametrically opposite but not in alinement with each other, the cylinder B being in register with the crank member d' and the cylinder B' in register with the crank member d, it being also seen 15 from the said Fig. 3 that the muffler-chambers are also alternately disposed, with reference to a line drawn centrally through the casing, (see X in Fig. 3,) whereby to bring the muffling and cooling chambers C at one side opposite the cylinder B and the chamber C' in 20 register with the cylinder B', such arrangement of parts being provided to effect a proper balancing of the motor.

E designates what I term the "main compression-chamber," which is axially situated with respect to the cylinders, and into the said chamber E extend the inner open ends d² of the hollow stationary shaft-sections D D', the outer ends of which are fixedly held 25 in the standards F F, and the said ends are threaded, as at d⁴, to receive coupling-elbows g g', to which connect the feed-pipes G G', that convey the explosive mixture from the vaporizer, (not shown,) which may be of any 30 well-known construction, combined with my improved motor or engine, as conditions may make desirable, and each of the said feed-pipes G G' has a back check-valve g^x, the reason for which will hereinafter be apparent.

40 The cylinders B B' are of like construction and of a diameter and length to suit the stroke of pistons desired, and in each of the cylinders operates a plunger-piston H H' of a special construction, which is best shown in Fig. 4, from which it will be observed the said plunger-pistons are in the nature of hollow heads h h', in which are mounted the cross-pins h² h³, with which connect the strap ends i i' of the pitmen or driver-arms I I', the inner ends of which have suitable journal-boxes i² i³ to engage with their respective crank members d d', as shown. Each head h h' has suitable packing-rings h^x, and the outer end of each of said heads has a cup-shaped extension h⁵, at one side of which is an outwardly-discharging pocket h⁶ and at the opposite side a receiving port or space h⁷, the reasons for which will be presently explained. The outer ends of the cylinders, for economy 55 of manufacture and ease of access thereto, are in the nature of detachable plugs J J.

The cylinders B B' have cooling-ribs B^x,

that project into the combined cooling and muffling chambers C C', as best shown in Fig. 3, and each of the said chambers C C' extends 70 segmentally at each side of the cylinders, and the said chambers C C' in that portion in advance of the cylinders—that is, on the down-going side—have radial fan-slots c c, which are so disposed to provide for a free ingress of 75 air within the said extensions C C', and at the rear of the cylinders the spaces C C' have apertures c' c' for the exhaust of the air, and as the said spaces C C' extend between the cylinders and the cap-plates L L (the latter 80 forming the outer walls of the said spaces C C') it follows that under a rapid motion of the motor through the air a constant circulation of air is maintained within the spaces C C', which muffles the noises produced with- 85 in the cylinder and serves to effectively cool the said cylinders and also the exhaust-passages, as hereinafter again referred to.

With each of the cylinders B B' connects a feed-port, and the said ports (designated M M') have their entrant ends in communication with the main compression-chamber E, and the said ports M M' are disposed diametrically opposite each other and adjacent to their respective cylinders B B'. The discharge 95 ends of the ports M M' are so disposed relatively to the stroke of the plunger-pistons that at no time are they in communication with that portion of the cylinders B B' inside of the rear or back end of the plunger-pis- 100 tons, and they are so arranged as to register with the pockets h⁶ of the said pistons when the latter reach the limit of their inward thrust, whereby to permit of the entrance of a charge of initially-compressed working 105 agent into the explosion end of the cylinders.

N N' designate exhaust-ports, one for each cylinder, which connect with the cylinders at points diametrically opposite the discharge-face of the inlets M M', and the said ports 110 N N' discharge into the first ones of a series of radially-disposed spaces O O', that communicate with each other through the staggerly-arranged openings o o in the several division-walls P P', (see Fig. 2,) and the last ones O⁵ O⁴ 115 of each set of the spaces O O' have an outlet-throat Q Q', which discharges to atmosphere and which extends under hood portions q q', projected into the combined cooling and moving spaces C C'. The ports N N', as will be noticed from the drawings, are located within that portion of the cooling-spaces over which the air-exhausts are so located within the said spaces that the air therein encircles them before escaping. 120

In my construction of engine provision is made for exploding the charge by electric sparking devices R R'. The terminals r r' are projected within the outer ends of the cylinders B B', as best shown in Fig. 2, and the said sparking devices are energized by the closing of the circuits connected therewith at proper predetermined times, which operation may be effected in any well-known 130

manner—for example, by mounting a spring-plate contact member S on one of the standards projected in the plane of an opposing contact-plate S', suitably mounted on the rotary portion of the motor and arranged to engage with the plate S at proper predetermined times—that is, when the working charge in advance of the plunger-piston is at the maximum compression.

10 The manner in which my invention operates is explained as follows: Assuming the motor-engine to be running in the direction indicated by the arrow in Fig. 2 and the plunger-pistons to be moving outwardly—that is, toward the heads of the cylinders—the said movement of the plungers will now create a vacuum within the central chamber E, and thereby suck in a charge of working agent from within the opposite hollow pipe-sections D D', the valves in the feed-pipes G G' now opening to admit of a free flow of the vapor, which then fills into the said chamber E, and assuming a prior working agent to be in each of the cylinders in front of the pistons said charges will now be being compressed to the maximum degree, and when this occurs the electric contacts that control the sparking devices will be in a closed engagement, and thereby ignite and explode 25 the said charges, which then impel the plungers backward. The backward thrust of the plungers pushes on and compresses the explosive mixture within the central chamber, and since the check-valves in the feed-pipes 30 G G' are now closed the said mixture is subjected to an initial compression. When the plungers reach the limit of their back thrust, the pockets h⁶ thereof will momentarily register with the discharge ends of the inlet-ports 35 M M', and the partially-compressed mixture within the chamber E will then flow into the cylinder ends in advance of the plunger, the curved faces of the pockets h⁶ on the plungers serving to deflect the said charge outward, (see 40 arrows on Fig. 6,) and the cup extensions h⁵ will trap the said charges and prevent them flowing directly toward the exhausts N N', which at this time are open to the upper end 45 of the cylinders, and by reason of the peculiar construction of the plunger or piston heads, as stated, the partially-compressed charge will in entering the extension ends of the cylinder 50 at once blow out the residuum or burned mixture contained therein through the ports or 55 ways h⁷ into the exhausts N N', it being understood that the operation of feeding the charge into the explosion-chamber and the blowing out of the burned mixture is an almost instantaneous one, as the plungers immediately begin to move outward and cut off 60 the inlets M M' and the exhausts N N' and compress the charging front of them to the maximum or exploding point.

Each of the exhaust-diffusing spaces or 65 chambers O O' is preferably formed with an opening o^x, normally closed by a screw-plug o^y, said openings being provided to permit of

cleaning out any deposits that may accumulate within the said spaces.

In the complete construction of my engine 70 a governor device for each inlet-port is used, and the said governor devices each consist of a two-way valve V, mounted within inlets to the cylinder, to the stem of which is secured a weight-arm T, normally moved to one position by a coil-spring U and to its other position by centrifugal force, it being readily understood that the varying loads on the engine in changing the momentum of the motor will shift the said arm to adjust the valve to 75 a full-open or to a closed position. While I prefer on the score of economy to use the governor such as described and shown in Fig. 7, it is obvious that any other centrifugal-acting governor mechanism may be used in connection with the motor devices, and, furthermore, while the general arrangement of the parts as shown and described is a preferred one it is manifest that the said parts may be modified or changed without departing from 80 the spirit of my invention and the scope of the appended claims.

From the foregoing, taken in connection with the accompanying drawings, it is believed the advantages of my invention and 85 the complete operation thereof will be readily understood.

Among other important advantages it should be stated that in my construction of 90 engine there is no necessity of separate balance-wheels to carry the several parts over the dead-center, and the said several parts are so joined that the entire engine of motor mechanism can be compactly assembled and in a manner convenient for using the same 95 for launches, automobiles, and motor-cycles.

Having thus described my invention, what I claim, and desire to secure by Letters Patent, is—

1. In a gas-engine as described, the combination with hollow stationarily-held shaft-section, vapor-feed devices connected therewith, a check-valve in each of said devices, a pair of stationary oppositely-projected cranks joined with the shaft-sections, a rotary casing for the cranks provided with a pair of oppositely-disposed cylinders and a series of exhaust-diffusing chambers communicating with said oppositely-disposed cylinders, said casing also being formed with a centrally-disposed collecting-chamber into which the hollow shaft-sections discharge the working agent, said oppositely-disposed cylinders having their peripheral ends opened, screw-plugs for closing said ends, said diffusing-chambers 110 having an exhaust-outlet and peripheral openings, plugs for closing said peripheral openings, a plunger-piston for each cylinder connected with the cranks, a feed-port for each cylinder, said ports communicating with the 115 centrally-disposed collecting-chamber, an exhaust-port for each cylinder connecting with said exhaust-diffusing chambers, said exhaust and said feed ports of the cylinders being con- 120 125 130

trolled by the shifting movement of the plunger-pistons, as set forth.

2. In an engine as described; in combination with a rotary casing, a stationary hollow shaft on which the said casing rotates, adapted to convey the explosive mixture therein, check-valve devices for preventing the escape of the mixture back through the shaft, said casing carrying a pair of oppositely-disposed cylinders, a pair of oppositely-disposed crank members fixedly connected with the shaft and located within the casing, a plunger-piston for each cylinder joined with each crank, said casing including a separate cooling and muffling space surrounding each cylinder, said space having air-inlets at one side of the cylinder and air-outlets at the other side thereof, feed-ports connecting the casing and the cylinders, and exhaust-ports connecting the cylinders with the atmosphere, said inlets and exhaust-ports being controlled by the shifting of the plunger-heads, as set forth.

3. In an engine of the character stated, the combination with a rotatable casing having a central collecting-chamber, a pair of open-ended cylinders formed within said casing, screw-plugs for closing the outer ends of said cylinders, the inner ends of said cylinders directly communicating with said central collecting-chamber, said cylinders having a feed-port at one side and an exhaust diametrically opposite to the feed-port, a series of exhaust-diffusing chambers having an exhaust-outlet communicating through said exhaust-ports with the cylinders, means for causing an air circulation around said cylinders, and means for cooling the outlet of the exhaust-diffusing chambers, of a plunger-piston movable within said cylinders and having portions for coop-

erating with the inlet and outlet ports at predetermined times, for the purposes described.

4. In an engine as described, a stationary hollow shaft, a casing rotatably mounted thereon, said casing having an axial collecting-chamber into which the hollow shafts discharge the working agent, a pair of fixedly held oppositely-disposed cranks within the casing, said casing having a pair of oppositely-disposed cylinders, a plunger-piston for each cylinder, a crank and feed-inlet connecting each cylinder with the crank-chamber of the casing, an exhaust-port connected with each cylinder, a series of hollow pockets within the casing connected with each other and with the exhaust-ports of the cylinders, said hollow pockets having an outlet-discharge into atmosphere and means for air-cooling the said cylinders and outlets, arranged substantially as shown and described.

5. In an engine of the character described, the combination of the rotary casing, the cylinders, the piston-plungers and drive-arms rotatable therewith, the stationary shaft and the cranks, and means for conveying the working agent into the casing and from thence into the cylinders, the said cylinders having exhausts, the casing having hollow spaces surrounding the cylinders, the outer walls of which at a point in advance of the cylinders having radially-disposed slots for the ingress of air and provided at a point to the rear of the cylinders with air-outlets, as shown and described.

GRANT C. BLASDELL.
